DRILLING IMPLEMENT GUIDE

John C. Curtis, Claremont, N. H., assignor to
 Sullivan Machinery Company, a corporation of
 Massachusetts

Application June 15, 1942, Serial No. 447,016

17 Claims. (Cl. 255—51)

This invention relates to rock drills and more particularly to improvements in a guide for the drill steel of a hammer rock drill of the mounted drifter type.

In rock drills of the mounted drifter type, a drill hammer motor for percussively actuating a drill steel, is usually mounted on the guideways of a guide shell, and the latter in turn is suitably supported with respect to the work. In such rock drills, a guide is often provided at the front end of the guide shell to center and guide the drill steel during starting or "spotting" of a drill hole. As the drill hammer motor is fed forwardly along the guideways of the guide shell and the forward end of the hammer motor approaches the drill steel guide, it is desirable to effect automatic release of the guide from the drill steel and to effect movement of the guide into its non-guiding position out of the path of movement of the hammer motor so that the latter may be fed along the shell guideways forwardly past the guide. It is also desirable to provide a guide structure which is relatively simple and rugged in design, light in weight and extremely compact, while providing for adequate centering and guiding of the drill steel.

It is an object of the present invention to provide a novel drill steel guide which embodies the desired features above outlined, in that it is not only automatically releasable and simple and rugged in design, but also provides for adequate centering and guiding of the drill steel. Another object is to provide a novel drill steel guide having improved mounting means for the guiding elements thereof. A further object is to provide improved resilient means for yieldingly holding the guiding elements in guiding position and for automatically moving the guiding elements into their non-guiding position when the holding means is released. Yet another object is to provide a novel drill steel guide having a combined torsion and compression spring for controlling movements of the guiding elements. A still further object is to provide an improved drill steel guide which is automatically releasable by engagement of the drill hammer motor therewith as the latter moves forwardly along its supporting guide. Still another object is to provide a novel drill steel guide of the pivoted guide arm type and embodying improved mounting means for the guide arms whereby the latter may be either separately or concurrently placed in a guiding relation with the drill steel. Another object is to provide a novel drill steel guide of the pivoted guide arm type having improved means for locking the guide arms in

guiding position and for automatically effecting swinging of the guide arms into their released non-guiding position when the locking means is released. A further object is to provide a novel spring arrangement for holding the guide arms in guiding position and for moving the guide arms into their released position. With the above and other objects in view, this invention relates to certain novel features of construction, operation and arrangement of parts, two examples of which are given in the specification and illustrated in the accompanying drawings, wherein:

Fig. 1 is a side elevational view of the forward portion of a rock drill equipped with a preferred illustrative embodiment of the drill steel guide.

Fig. 2 is a front end elevational view of the rock drill and drill steel guide shown in Fig. 1, the drill steel being shown in cross section.

Fig. 3 is a cross sectional view taken substantially on line 3—3 of Fig. 1, showing the drill steel guide in its guiding position.

Fig. 4 is a view similar to Fig. 3, showing the drill steel guide in its released non-guiding position.

Fig. 5 is a horizontal sectional view taken substantially on line 5—5 of Fig. 1.

Fig. 6 is a fragmentary cross sectional view taken substantially on line 6—6 of Fig. 1.

Fig. 7 is a fragmentary view in longitudinal vertical section taken substantially on line 7—7 of Fig. 2.

Fig. 8 is a side elevational view similar to Fig. 1, illustrating a modified embodiment of the drill steel guide.

Fig. 9 is a front end elevational view of the rock drill and drill steel guide shown in Fig. 8, with parts shown in vertical section.

Fig. 10 is a cross sectional view taken substantially on line 10—10 of Fig. 8, showing the drill steel guide in its released non-guiding position.

Fig. 11 is a horizontal sectional view taken substantially on line 11—11 of Fig. 8.

Fig. 12 is a fragmentary view in longitudinal vertical section taken substantially on line 12—12 of Fig. 9.

Fig. 13 is a fragmentary view in longitudinal vertical section taken substantially on line 13—13 of Fig. 9.

In both illustrative embodiments of the invention which is an improvement over that disclosed in a copending application Ser. No. 411,283, filed Sept. 18, 1941, of which I am one of the joint inventors, the improved drill steel guide is shown associated with a conventional hammer rock drill of the mounted drifter type. It will be evident,

however, that the invention may be embodied in drills of other types.

The rock drill disclosed herein comprises a conventional hammer motor 1 slidably guided on a conventional guide shell 2, the latter being adapted to be mounted on any suitable support. The drill hammer motor has a motor cylinder 3 containing a reciprocable hammer piston (not shown) for percussively actuating a drill steel 4, the latter being suitably supported in a usual chuck within a front chuck housing 5 suitably attached to the forward end of the motor cylinder. The motor cylinder has usual lateral guides 6, 6 slidably received in longitudinal guideways 7, 7 of the guide shell. The hammer motor may be fed in a well known manner along the shell guideways toward and from the work by means of a conventional feed screw 8 journaled on the guide shell and engageable with a feed nut carried by the hammer motor so that when the feed screw is rotated, the hammer motor is fed along the shell guideways. Since, as stated above, the rock drill is of a conventional design and is well known to those skilled in the art, further description and illustration thereof are herein unnecessary.

Now referring to the preferred embodiment of the invention shown in Figs. 1 to 7 inclusive, it will be noted that the drill steel guide generally designated 9 includes front and rear transverse plates 10 and 11, attached by bolts 12, herein preferably three in number, to the front end of the guide shell 2 (Fig. 5). These transverse plates are held in spaced parallel relation by spacing sleeves 13 surrounding the bolts between the plates, as shown. In this instance, the rear plate 11 has an integral bearing boss 14 in which the front bearing portion of the feed screw 8 is journaled. Pivotaly mounted on the spacing sleeves 13 of the upper pair of bolts, is a pair of cooperating guide arms 15, 15 each having an appropriately shaped guiding portion 16. The guiding portions 16 of the guide arms are engageable with the body of the drill steel 4 to hold the latter centered during starting or "spotting" of a hole in a manner well known to those skilled in the art. The guide arms are also mounted on the spacing sleeves 13 of the upper pair of bolts for bodily or translatory sliding movement relative thereto between the plates 10 and 11, and the guide arms have near their pivots downwardly projecting locking lugs 17 engageable, when the arms are in their rearmost guiding position, with opposite vertical side surfaces 18 of the rear plate 11 (see Figs. 1 and 6). As shown, projecting rearwardly from the rear faces of the guide arms are abutment bosses 19 with which the front end of the chuck housing 5 of the drill hammer motor is engageable. A spring 20 common to both guide arms has coiled portions 21, 21 encircling the spacing sleeves 13 of the upper pair of bolts and these coiled portions are interposed between the front surfaces of the arm hubs 22 and the rear face of the front plate, as clearly shown in Fig. 5. The coiled portions 21 are connected together by a cross portion 23 extending therebetween, and the end portions 24 of the spring engage the inner sides of the guide arms. The arm hubs 22 are recessed at 25 to receive portions of the spring coils and the hubs are laterally cut away at 26 so as to provide clearance for the hammer motor guides 6, 6 when the guide arms are swung into their wide open position, as shown in Fig. 4. The inner sides of the arms are recessed at 27 to receive the end portions 24

of the spring. The spring urges the guide arms rearwardly into their locked position shown in Fig. 1 in abutting relation with the rear plate and with the locking lugs 17 in locking engagement with the plate surfaces 18. The coiled portions 21 of the spring also serve automatically to swing the guide arms about their pivots from their guiding position to their released non-guiding position shown in Fig. 4, when the locking lugs 17 are released from the plate surfaces 18. The lugs 17 on the guide arms, when the arms are swung apart as shown in Fig. 4, engage the lower portion of the bearing boss 14 thereby to limit outward swinging of the arms. When the arms are wide apart, the drill hammer motor may move forwardly along the shell guideways past the guide, and as will later be described, the arms are shoved bodily forwardly to effect release of the locking lugs by engagement of the front end of the hammer motor with the abutment bosses 19 on the guide arms. Thus the spring has both compression and torsion functions and the coiled torsion spring portions react on the arms themselves, therebetween.

The modified embodiment of the invention shown in Figs. 8 to 13 inclusive is generally similar to that above described. In this construction, however, the coiled portions of the spring are removed from the vicinity of the arm pivots so that there is no cooperation between the spring and the arm pivot bearings. Also, in this instance, the spring does not act on the arms to move the latter rearwardly into their locked guiding position. As shown, the hubs 29 of the guide arms 15' are formed with longitudinal bores 30 which receive spring-pressed plungers 31 acting against the rear face of the front plate 10, and the plunger springs urge the guide arms rearwardly, in the locked guiding position of the latter, against the rear plate 11. A torsion spring 32 has coiled torsion portions 33 received in recesses 34 formed in brackets 35 secured to the front surfaces of the guide arms. These spring brackets are arranged forwardly of the front plate 10 in advance of the attaching bolts, in longitudinally spaced relation with respect to the guide arm pivots (Fig. 11). A cross connecting portion 36 of the spring extends between the spring coils, and the spring brackets are slotted at 37 to clear the cross spring portion as the guide arms swing about their pivotal axes. These brackets are also cut away at 38 to provide clearance for the hammer motor guides when the guide arms are in their wide open position shown in Fig. 10. The end portions 39 of the spring are engaged in notches 40 in the spring brackets (Fig. 12). Otherwise, this embodiment of the invention is generally similar to that above described.

It will be evident that in lieu of the single spring having coiled portions in coincidence with the arm pivot axes, separate torsion springs, one individual to each guide arm, may be employed. In such a separate spring arrangement, it would be necessary to connect the springs between the arms and parts stationary with the front plate to provide suitable points of reaction for the springs, in an obvious manner.

In the operation of the preferred embodiment of the drill steel guide above described, when it is desired to start or "spot" a drill hole the guide arms 15 may be swung about their pivots into the guiding position shown in Figs. 1, 2 and 3 with the guiding portions 16 in engagement with the body of the drill steel 4, and at that time, the guide arms are locked in guiding

position by engagement of the locking lugs 17 with the vertical surfaces 18 on the rear plate. As the drill hammer motor 1 is fed forwardly along the shell guideways 1, 1, the front chuck housing 5 engages the abutment bosses 19 on the guide arms and, upon continued forward movement, shoves the arms forwardly bodily along the spacing sleeves on which they are mounted, to effect release of the locking lugs 17 from the plate surfaces 18. When the guide arm locks are released, the torsion spring 20 acts automatically to throw the guide arms into their wide open non-guiding position shown in Fig. 4, so that the drill hammer motor may move forwardly between the guide arms without interference therewith. Under certain conditions, the guide arms may be separately placed in guiding relation with the drill steel so that but a single guide arm may serve as a guide, for instance during "spotting" of a drill hole on an inclined surface when but a single guide arm will suffice to prevent lateral deflection of the steel. When it is desired again to position the guide arms 15 in guiding relation with the drill steel, the operator may manually swing the arms against the tension of the torsion spring 20 into engagement with the drill steel and then shove the guide arms bodily rearwardly into abutting engagement with the rear plate 11 with the arm locking lugs 17 in locking engagement with the plate surfaces 18.

The operation of the modified embodiment of the invention is generally similar to that above described, in that the guide arms move into and out of guiding relation with respect to the drill steel in a substantially similar manner. In this instance, however, the guide arms are swung apart by the torsion spring 32 and are moved rearwardly into their locked guiding position by the springs associated with the plungers 31. The guide arms are released from their locked guiding position by engagement of the chuck housing of the drill hammer motor therewith as in the preferred embodiment of the invention, and the guide arms are shoved bodily forwardly into their released position against the action of the springs associated with the plungers. When the guide arm locks are released, the torsion spring 32 automatically swings the guide arms into the wide open non-guiding position shown in Fig. 10. The guide arms may be moved manually into their guiding position in substantially the same manner as in the preferred embodiment of the invention above described.

As a result of this invention, it will be noted that an improved drill steel guide is provided which is not only relatively simple and compact in design, but is also rugged in construction. It will further be evident that by mounting the guide arms in the manner disclosed, the locking means is simplified, and further by the particular arrangement of the torsion spring, the guide arms are automatically swung into their released non-guiding position in an extremely effective manner. Further, by means of the particular mounting and locking arrangement for the guide arms, the latter are released from their guiding position by direct engagement of the chuck housing of the drill hammer motor therewith, thereby eliminating relatively complicated release devices. The improved guide may also be readily attached to a guide shell of a conventional design. Other uses and advantages of the invention will be clearly apparent to those skilled in the art.

While there are in this application specifically described preferred and modified embodiments which the invention may assume in practice, it will be understood that these preferred and modified embodiments are shown for purposes of illustration and that the invention may be further modified and embodied in various other forms without departing from its spirit or the scope of the appended claims.

10. What I claim as new and desire to secure by Letters Patent is:

1. In a drill steel guide, a pair of cooperating guiding elements movable laterally into engagement with a drill steel and translationally longitudinally of the drill steel, mounting means for said guiding elements, means for holding said guiding elements in steel guiding position, and resilient means connected between and engaging said guiding elements for automatically independently moving said guiding elements laterally away from the drill steel into their released non-guiding position when said holding means is rendered ineffective, said resilient means comprising a coil torsion spring having oppositely acting coil portions, one coil portion acting on each guiding element, and said coil portions urging said guiding elements translationally into the position wherein they are held by said holding means in guiding relation with the steel.
2. In a drill steel guide, a pair of cooperating guiding elements engageable with a drill steel, mounting means for said guiding elements, means for holding said guiding elements in steel guiding position, and resilient means connected between and engaging said guiding elements for automatically moving said guiding elements into their released non-guiding position when said holding means is rendered ineffective, said resilient means comprising a coil torsion spring having oppositely acting coil portions, one coil portion acting on each guiding element, and said coil portions urging said guiding elements translationally into the position wherein they are held by said holding means in guiding relation with the steel.
3. In a drill steel guide, a pair of cooperating guiding elements engageable with a drill steel, mounting means for said guiding elements, means for holding said guiding elements in steel guiding position, and resilient means connected between and engaging said guiding elements for automatically moving said guiding elements into their released non-guiding position when said holding means is rendered ineffective, said resilient means also yieldingly urging said guiding elements into a position to render said holding means effective.
4. In a drill steel guide, a pair of cooperating guiding elements movable laterally toward and from one another into and out of guiding relation with a drill steel and translationally longitudinally of the steel, mounting means for said guiding elements, means for holding said guiding elements in their steel guiding position and releasable upon translatory movement of said guiding elements, and resilient means for moving said guiding elements laterally away from the drill steel into their released non-guiding position when said holding means is rendered ineffective, said resilient means comprising a torsion spring engaging and acting between said guiding elements, said torsion spring having oppositely acting coil portions, one coil portion acting on each guiding element and said coil portions serving to urge said arms translationally toward their held position.
5. In a drill steel guide, a pair of cooperating guiding elements movable toward and from one

another into and out of guiding relation with a drill steel, mounting means for said guiding elements, means for holding said guiding elements in their steel guiding position, and resilient means for automatically moving said guiding elements into their released non-guiding position when said holding means is rendered ineffective, said resilient means comprising a torsion spring extending and acting between said guiding elements, said spring being supported by said guiding elements in a position spaced in a direction lengthwise of the drill steel from the mounting means for said guiding elements.

6. In a drill steel guide, a pair of cooperating guiding elements movable toward and from one another into and out of guiding relation with a drill steel, mounting means for said guiding elements, means for holding said guiding elements in their steel guiding position, and resilient means for automatically moving said guiding elements into their released non-guiding position when said holding means is rendered ineffective, said resilient means comprising a torsion spring extending and acting between and engaging said guiding elements, said resilient means also holding said guiding elements yieldingly in their guiding position wherein they are held by said holding means.

7. In a drill steel guide, mounting means, a pair of guide arms supported by said mounting means for pivotal and translatory movements with respect thereto, means for locking said guide arms in their guiding position, said locking means being releasable upon translatory movement of said guide arms with respect to said mounting means, and resilient means common to both guide arms and engaging the latter for yieldingly holding said guide arms in locked position and for automatically swinging said guide arms about their pivots into their non-guiding position when said locking means is released.

8. In a drill steel guide, mounting means, a pair of guide arms supported by said mounting means for pivotal and translatory movements with respect thereto, means for locking said guide arms in their guiding position, said locking means being releasable upon translatory movement of said guide arms with respect to said mounting means, and resilient means common to both guide arms for yieldingly holding said guide arms in locked position and for automatically swinging said guide arms about their pivots into their non-guiding position when said locking means is released, said resilient means comprising a torsion spring extending and acting between and engaging said guide arms for effecting both pivotal and translatory movements of the latter.

9. In a drill steel guide, mounting means, a pair of guide arms supported by said mounting means for pivotal and translatory movements with respect thereto, means for locking said guide arms against pivotal movement in their steel guiding position, said locking means being releasable upon translatory movement of said guide arms with respect to said mounting means, and resilient means for yieldingly holding said guide arms in locked position and for automatically swinging said guide arms about their pivots into their non-guiding position when said locking means is released, said resilient means comprising a torsion spring extending and acting between and engaging said guide arms, said torsion

spring also urging said arms translationally toward locked guiding position.

10. In a drill steel guide, a support, a pair of cooperating guide arms mounted on said support to swing into and out of guiding relation with a drill steel and for translatory movement longitudinally of the steel, and a coil torsion spring engaging and acting between said guide arms for swinging said arms in one direction about their pivots, said spring having torsion coils, one coil acting on each guide arm for swinging the latter, and said coils also serving to urge said arms translationally in one direction.

11. In a drill steel guide, a support, a pair of cooperating guide arms pivotally mounted on said support to swing into and out of guiding relation with a drill steel, means for locking said arms to said support in guiding position, and a spring extending and acting between said guide arms and engaging the latter for swinging said guide arms in one direction about their pivots, said spring having coiled portions arranged in coaxial relation with the arm pivots, and said coil portions serving to urge said locking means toward arm locking position.

12. In a drill steel guide, a support, a pair of cooperating guide arms pivotally mounted on said support to swing into and out of guiding relation with a drill steel and having translatory movement relative to said support longitudinally of the drill steel, and a spring extending and acting between said guide arms and engaging the latter for swinging said guide arms in one direction about their pivots, said spring having coiled portions arranged in coaxial relation with the arm pivots but in longitudinally spaced relation with respect to the arm pivot bearings, and said coil portions opposing translatory movement of said guide arms in one direction.

13. In a drill steel guide, a support, a pair of cooperating guide arms pivotally mounted on said support to swing into and out of guiding relation with a drill steel and having translatory movement relative to said support longitudinally of the drill steel, and a spring extending and acting between said guide arms and engaging the latter for swinging said guide arms in one direction about their pivots, said spring having coiled portions arranged in coaxial relation with the arm pivots, said coiled portions having a cross-connecting portion extending therebetween, and said coil portions serving to oppose translatory movement of said guide arms in one direction.

14. In a drill steel guide, a support, a pair of cooperating guide arms mounted on said support for pivotal and translatory movements with respect thereto, and a spring common to said guide arms and engaging the latter for effecting both the pivotal and translatory movements of said guide arms.

15. In a drill steel guide, a support, a pair of cooperating guide arms mounted on said support for pivotal and translatory movements with respect thereto, means for locking said guide arms to said support in their guiding position in engagement with a drill steel, said locking means being releasable upon translatory movement of said guide arms with respect to said support, and a torsion spring common to and connected between said guide arms and engaging the latter for swinging said arms apart when said locking means is released, said torsion spring having outwardly acting ends, one spring-end engaging each guide arm between the arm pivot and steel engaging end of the arm.

16. In a drill steel guide, a support, a pair of cooperating guide arms mounted on said support for pivotal and translatory movements with respect thereto, means for locking said guide arms to said support in their guiding position in engagement with a drill steel, said locking means being releasable upon translatory movement of said guide arms with respect to said support, and a spring common to and connected between said guide arms and engaging the latter for swinging said arms apart when said locking means is released, said spring having coil portions in coaxial relation with the arm pivots.

17. In a drill steel guide, a support, a pair of

cooperating guide arms mounted on said support for pivotal and bodily movements with respect thereto, means for locking said guide arms in their guiding position, said locking means being 5 releasable upon bodily movement of said guide arms with respect to said support, a spring common to and connected between said guide arms for swinging the latter apart when said locking means is released, and spring means separate and 10 distinct from said spring for bodily moving said guide arms toward their locked position, said spring means comprising spring-pressed plungers mounted on said guide arms respectively.

JOHN C. CURTIS.
